UNITED STATES PATENT OFFICE.

MELA C. BROWN, OF EUGENE, OREGON

MILK-BOTTLE CAP.

1,094,639.

Specification of Letters Patent. Patented Apr. 28, 1914.

Application filed September 25, 1913. Serial No. 791,835.

To all whom it may concern:

Be it known that I, MELA C. BROWN, a citizen of the United States, residing at Eugene, in the county of Lane and State of Oregon, have invented certain new and useful Improvements in Milk-Bottle Caps, of which the following is a specification, reference being had therein to the accompanying drawing.

10 This invention relates to a milk bottle cap and has for its object the production of a cap which is provided with a simple and efficient means for closing the upper portion of the bottle and which is also provided with 15 means for stiffening or reinforcing the body portion of the cap so as to prevent the milk from leaking out around the body portion of the cap.

Another object of the invention is the production of a milk bottle cap which is provided with a plurality of lips which are adapted to firmly engage the upper portion of the milk bottle for firmly holding the cap in position thereon.

25 With these and other objects in view this invention consists of certain novel combinations, constructions and arrangements of parts as will be hereinafter fully described and claimed.

30 In the accompanying drawing: Figure 1 is a central vertical section through the upper portion of the milk bottle and the improved cap, showing the cap as it appears when first placed upon the bottle. Fig. 2 is 35 a view similar to Fig. 1 showing the lips bent so as to firmly engage the upper portion of the bottle for holding the cap in position. Fig. 3 is a bottom plan view of the cap. Fig. 4 is a top plan view of the same.

40 Referring to the accompanying drawing by numerals it will be seen that the cap comprises a primary and auxiliary section. The primary section is provided with the central round body 1 while the auxiliary section is 45 provided with a similar body 2. A round reinforcing disk 3 is positioned between the bodies 1 and 2 so as to firmly reinforce the same thereby the milk within the bottle will be prevented from seeping through the

50 bodies 1 and 2. Furthermore this reinforcing disk 3 will prevent or lessen the danger of a foreign object striking the bodies and punching a hole therein, and will at the same time cause the outer portion of the

bodies to efficiently bind within the upper 55 portion of the neck of the bottle. This cap may be used in combination with an ordinary bottle 4 having a pocket 5 wherein the bodies 1 and 2 and the reinforcing disk 3 are adapted to fit. The outer portion in 60 each body is provided with a plurality of substantially U-shaped lips 6. These lips 6 extend downwardly for a determined distance below the lower portion of the bodies 1 and 2. It is preferred that this cap be 65 formed of waxed paper or the like so as to resist any tendency of the liquid to penetrate the same.

When this cap is used it is placed upon the bottle as illustrated in Fig. 1 at which 70 time the lips 6 may be extended, as shown in full lines, or may extend upwardly as illustrated in dotted lines. By placing the cap upon the bottle in this place, the lips will easily pass over the outer portion of 75 the bottle while the bodies 1 and 2 and the disk 3 will pass down into the pocket 5 of the bottle for efficiently closing the same. The lips 6 may then be bent inwardly as illustrated in Fig. 2 and in dotted lines in 80 Fig. 1 for efficiently holding the cap upon the bottle and at the same time prevent any dirt from entering the bottle around the upper portion thereof. Since the lips are formed of wax paper, as above stated, after 85 the same are bent inwardly they will snugly fit upon the upper portion of the bottle for forming a tight closure for the same.

By referring to Fig. 3 it will be seen that the lips of the body 1 are formed in staggered relation to the lips upon the body 2, thereby causing the space between the lips of one body to be covered by the lips of the other body, thereby preventing moisture from passing between the lips and into the 95 milk bottle. Furthermore, it will be seen that the side edges of the lips of both bodies engage each other when the cap is in use, thereby allowing the lips formed upon the body 2 to fit firmly and squarely upon the 100 milk bottle 4, and in this manner prevent refuse or dirt from passing up under the lips.

From the foregoing description it will be seen that a simple and efficient milk bottle 105 cap has been produced which will efficiently close the upper portion of a bottle for preventing the entrance of dirt thereinto and

which also is provided with a simple means for firmly and snugly holding the cap upon the bottle.

Having thus described the invention what is claimed as new, is:—

As a new article of manufacture, a milk bottle cap comprising a pair of central round bodies, a plurality of lips integrally formed upon each of said bodies, said bodies and lips being waxed to form a yieldable water-proof structure, a stiff reinforcing disk interposed between said bodies, said bodies and disk adapted to fit in the upper portion of a milk bottle for forming a closure therefor, the side edges of each lip diverging toward the outer end of each lip, said lips adapted to fit over the neck of a milk bottle and snugly engage the bottle without the aid of secondary securing

means, each lip adapted to snugly engage the side edges of the adjacent lips when the cap is in use, thereby allowing the lips engaging the bottle to fit squarely upon the bottle, thereby forming a tight closure, and the lips upon one body being formed in staggered relation to the lips on the other body, whereby the space between the lips of one body will be covered by the lips of the other body, thereby preventing moisture from passing between the lips and into the bottle.

In testimony whereof I hereunto affix my signature in presence of two witnesses.

MELA C. BROWN.
